CLAIM

An ornamental design for a tissue culture flask, as shown and described.

DESCRIPTION

FIG. 1 is a perspective view of the tissue culture flask showing my new design;

FIG. 2 is a front view thereof on an enlarged scale;

FIG. 3 is a rear view thereof on an enlarged scale;

FIG. 4 is a left side view thereof on an enlarged scale;

FIG. 5 is a top plan view thereof on an enlarged scale;

FIG. 6 is a bottom plan view thereof on an enlarged scale;

FIG. 7 is a fragmentary cross sectional view thereof taken along section line 7—7 of FIG. 4.

The right side view not shown is the mirror image of the left side view shown in FIG. 4.
